UNITED STATES PATENT OFFICE.

PERRY O. BROWN, OF ST. VINCENT, MINNESOTA, ASSIGNOR OF ONE-HALF TO G. V. BACKSTROM, OF ST. VINCENT, MINNESOTA.

OIL CUP.

Application filed May 14, 1925. Serial No. 30,319.

To all whom it may concern:

Be it known that I, PERRY O. BROWN, a citizen of the United States, residing at St. Vincent, in the county of Kittson and State 5 of Minnesota, have invented certain new and useful Improvements in Oil Cups, of which the following is a specification.

The present invention relates to an oil cup for bearings and is particularly designed for machinery having a continuous 10 operation.

The principal object of the invention is to provide an oil cup, which has means incorporated therein, for actuating a force 15 feed of the oil, which is brought into operation by the bearing becoming heated.

Another very important object of the invention is to provide an oil cup, which has provision for allowing a continuous dripping 20 of oil onto a bearing and operates a thermo-statically controlled forced oil feed, which will be brought into operation when the bearing becomes overheated or tends to become overheated.

25 A still further important object of the invention is to provide an oil cup of this nature, which may be easily and quickly actuated, to be brought into operation or to be placed out of operation when the machine is 30 stopped.

Another object of the invention is to provide an oil cup of this nature, which is exceedingly simple in construction, inexpensive to manufacture, efficient, reliable, not 35 likely to become out of order, and otherwise well adapted to the purpose for which it is designed.

With the above and numerous other objects in view, as will appear as the description 40 proceeds, the invention resides in certain novel features of construction, and in the combination and arrangement of parts as will be hereinafter more fully described and claimed.

45 In the drawing:

Figure 1 is an elevation of the oil cup embodying the features of my invention.

Figure 2 is an enlarged vertical section therethrough.

50 Figure 3 is a horizontal section therethrough, taken on the line 3-3 of Figure 2, looking downwardly.

Figure 4 is a horizontal section therethrough, taken substantially on the line 4-4 55 of Figure 2.

Figure 5 is a perspective view of the plunger, and

Figure 6 is a sectional view, taken through the control means for the shut off needle valve.

60 Referring to the drawing in detail, it will be seen that 5 designates a block having the threaded extension 6, in order that the same may be engaged in a bearing as the ordinary oil cup. This block is provided with 65 a compartment 7, and a passage 8. A cap 9 is held over the block 5, by means of suitable fastening elements 10, and has a compartment 11 registering with the compartment 7, so as to form therewith a mercury 70 chamber. The chamber has an upwardly extending cylindrical portion 12. A stopper 13 is also provided in the chamber, in order that the same may be filled with the mercury. A cylinder 14 is engaged on the extension 12 and receives a receptacle 15 at 75 its upper end. The bottom of the receptacle is indicated by the numeral 16, and is provided with an opening 17, in which is disposed a valve seat cage 18, having the openings 19. A guide 20 is provided, on the lower end of the valve seat cage 18. A threaded opening 21 is provided in the side of the cylinder 14 and receives a pipe section 22. A cylindrical casing 23 is engaged 80 with the pipe section 22, and the axis thereof extends parallel with the axes of the cylinder 14 and the receptacle 15. The lower portion of the casing 23 has its interior restricted to form a valve seat 24. A tube, 85

90 preferably of glass, is indicated at 25, and extends downwardly from the coupling 26, communicating with the bottom end of the casing 23. A tube 27 communicates with the tube 25 and extends through the cap 95 9 and the block 5 for feeding oil to the bearing. A needle valve 29 is provided with a shank 30, movable through the cap 31, of the casing. A disc 32 is threadably associated with a sleeve 33, on the nipple 34 of the cap 31, and the shank 30 extends through the nipple 34, through the sleeve 33 and through the disc 32, and terminates in a lateral extension 35, in which is pivoted a lever 36, having a cam 37 100 formed thereon, for association with the disc 32. A nut 38 is threaded on the shank 30, within the casing, and a spring 39 is disposed about the shank, within the casing, impinging against the cap 31 and 110

against the nut, and has a tendency to normally hold the needle valve 29 closed. By actuating the lever 36, to the position shown in Figure 6, the needle valve may be raised, 5 and the distance between the valve and seat may be controlled by the adjustment of the disc 32. When the lever 36 is swung upwardly, the spring 39 will close the valve.

A level indicating tube 40 is associated 10 with the receptacle 15. A plunger 41 is provided with a tubular shank 42, having a solid head 43 on its lower end, and a head 44 on its upper end provided with an opening 45, communicating with the interior of 15 the tubular shank 42. This plunger is located with the head 43, slideable in the extension 12, and head 44, slideable in the cylinder 14. A needle valve 46 has its shank extended through the opening 45 and into 20 the interior of the shank 42. This needle valve extends into the valve cage 18. A spring 47 is disposed about the shank of the needle valve, between the plunger 41 and a shoulder 48.

25 The cylinder 14 is filled with suitable lubricating oil, and this is accomplished by first filling the receptacle 15, through the removable cap 49, and the receptacle 15 is also filled, the level of the oil therein, being indicated through the level indicating 30 tube 40. The lever 36 is then pushed down, so as to lift the needle valve 29 from the valve seat 24. The space between the needle valve 29 and the valve seat 24 is adjusted, by 35 operating the adjustment disc 42, so that the oil will drip as fast as desired, this being capable of ascertainment, by observing the oil dripping through the glass tube 25. While the device is thus operating in connection 40 with the bearing, it will be seen that should the bearing become heated, the mercury in the chamber formed by compartments 7 and 11 will expand, thereby pushing upwardly on the head 43 of the plunger 45 41, so as to cause the upward movement of the head 44, which will compress the spring 47 so as to close the needle valve 46 and the continued upward movement of the head 44 will force the oil in the cylinder 14 50 through the bight section 42 and through the casing, through the coupling 26, through the tube 25, and through the tube 27 to the bearing. This will be a force feed, and thus the bearing should soon cool to the 55 normal temperature. In order to prevent the oil from being forced upwardly in the casing, it is preferable to provide a plunger 50 on the shank of the needle valve 29, which will operate as a piston, in the upper 60 portion of the casing 23.

The construction, operation, and advantages of this invention should be readily understood, without a more detailed description.

It is apparent that numerous changes in 65 the details of construction, and in the combination and arrangement of parts may be resorted to, without departing from the spirit or scope of the invention as herein-after claimed, or sacrificing any of its advantages. 70

Having thus described my invention, what I claim as new is:

1. A lubricating device of the class described including a cylinder, a reservoir below the cylinder, a receptacle above the cylinder, a valve seat disposed between the receptacle and the cylinder, a valve associated with the seat, a plunger including a head slideable in the cylinder and a head 80 slideable in the reservoir, a thermally expansible fluid in the reservoir, said cylinder provided with an oil outlet, a resilient connection between the plunger in the cylinder and the valve, whereby when the material in the reservoir is expanded, the plunger will be moved, so as to move the head in the cylinder, so as to close the valve through the resilient connection, and force the oil from the cylinder, without interfering with the oil in the receptacle. 85

2. A lubricating device of the class described, including a cylinder having an outlet, a receptacle engaged in the upper end of the cylinder, a reservoir communicating with the lower end of the cylinder, a plunger including a tubular shank having a solid head slideable in the reservoir and a head slideable in the cylinder and provided with an opening communicating with the interior of the shank, a needle valve having a shank extending through the head having the opening and terminating in the tubular shank, a valve seat disposed between the cylinder and the receptacle, a shoulder 90 formed on the shank of the needle valve, a spring disposed about the needle valve between the shoulder and the plunger in the cylinder, said needle valve being normally open, said reservoir adapted to contain a thermally expansible fluid, so as to raise the plunger in the reservoir when heated, thereby raising the plunger in the cylinder for compressing the spring to close the needle valve and force the oil in the cylinder therefrom without interfering with the oil in the receptacle. 100

In testimony whereof I affix my signature.

PERRY O. BROWN.
